ACOUSTIC DEVICE

Filed Dec. 16, 1927

UNITED STATES PATENT OFFICE

MAX PAUL BONNAT, OF NEW YORK, N. Y., ASSIGNOR OF ONE-HALF TO PETER PODELL CO. INC., OF NEW YORK, N. Y., A CORPORATION OF NEW YORK

ACOUSTIC DEVICE

Application filed December 16, 1927. Serial No. 240,509.

This invention relates to improvements in acoustic devices, and more particularly to the diaphragm or sound regenerator of a radio loud speaker unit.

Among the radio loud speaker units now upon the market is the cone loud speaker, one form whereof is shown in the patent to Hopkins No. 1,271,529, granted July 2, 1918.

Loud speakers of this type employ the cone element as the diaphragm. The cone is closed at the apex and is secured at that point to the driving unit. At the point of juncture the cone is invariably reinforced or stiffened with one or more metal washers. The body of the cone possesses the characteristics of a membrane and constitutes a diaphragm for reproducing sound. The apex or point of juncture with the driving unit is not resilient and is consequently not receptive to vibrations and, therefore, constitutes a "dead spot" which impairs the quality of the sounds emitted by the cone. This tends to impair the acoustical properties of the loud speaker unit.

The object of this invention is a more efficient form of acoustic device.

Another object of this invention is the elimination of distortion.

In accordance with this invention the acoustic device comprises a diaphragm made in the form of a frustum of a hollow cone, the sound reproducing apparatus being connected to the smaller aperture of the cone.

In the drawings comprising but a single sheet of six figures, the invention is diagrammatically set forth.

Figure 1 is a sectional view of one form of the device;

Figure 2 is a sectional view of one alternative form;

Figure 3 is an enlarged sectional view of some of the parts of the device of Figure 1, showing certain details of construction;

Figure 4 is an enlarged front view of some of the parts of Figure 1 looking at said figure from the right;

Figure 5 is a perspective of one of the details of construction; and

Figure 6 is a perspective of certain other details of construction.

Like reference characters designate like

parts throughout the several figures of the drawings.

The body 7 defines a frusto-conical tubular diaphragm. It may be made of any preferred material; parchment, stiff paper, or even very thin metal may be employed, so long as the material used has the characteristic thinness of a membrane.

If the body 7 is made of metal it should be corrugated. Where metal is thus employed aluminum has been found to give very satisfactory results.

The body 7 may be formed from a blank sheet the ends whereof are secured together so that the whole defines the frustum of a hollow cone. The ends of the body portion may be united by means of a suitable cement or glue. When thus united the body 7 presents the appearance shown in Figures 1 and 2. The outer edge 8, which may be either free or clamped as preferred, defines the mouth of a frusto-conical tube and the inner edge 9 defines the throat 11 thereof. A suitable annular reinforcing strip 10 is secured to the body 7 adjacent the edge 9. This reinforcing strip furnishes additional strength adjacent the throat 11.

If the outer edge 8 is a free edge it is preferably reversely bent as indicated at 12 in Figures 1 and 2. This tends to furnish additional strength to the free edge of the cone and to maintain the body portion 7 tightly stretched.

Means are provided for securing the diaphragm to the driving rod of the sound reproducing apparatus. This means preferably comprises a plurality of rivets 15, a plurality of metal clips 13 of the character disclosed in Figure 5, each of which is provided with holes as at 14 to permit the insertion of the rivet 15 (Figure 3); and a plurality of metal vibrating strips 16 each provided with a base member 17 having a suitable aperture therein to permit the insertion of a rivet 15.

A clip 13 is placed under the metal strip 16 at the point where it is secured to the inner edge 9, and a light hollow rivet 15 is passed through apertures in the body portion 7, reinforcing strip 10, clip 13 and base member 17, and the several parts are then

riveted securely together. The metal vibrating strips 16 may be made either single or double. In the drawings a suitable double form is shown. When used double the strips are bent to define two sides of a triangle, the apex being flattened and provided with an aperture for use as hereinafter set forth. Whether single or double vibrating strips are used, the apertures 18 are all brought into alignment and the threaded stem 19 of the connecting sleeve 20 is inserted therein and the nut 21 is tightened upon the threaded stem 19 until the vibrating strips 16 are clamped tightly together.

If an even number of strips 16 is used the strips are preferably double, as shown in the drawings, but if an odd number of strips is used they may be made singly. The strips 16 should be equally spaced around the inner edge 9, as is best indicated in Figure 4, which illustrates the preferred arrangement to be followed where two double strips 16 are employed.

The driving rod of the sound reproducing apparatus is inserted in the bore 22 of the connecting sleeve 20 and the screw 23 is tightened to unite the driving rod to the connecting sleeve. Any movement of the driving rod is thus transmitted to the body 7 (which constitutes a diaphragm) by way of the vibrating strips 16. As the strips 16 are made of metal they transmit the vibrations imparted to them more readily and more rapidly than would be the case if the driving rod was secured to a non-metallic medium, as was customary in the prior art.

The inner edge 9 of the frusto-conical tube will be flexible at practically every point throughout its circumference, the only rigid points being those where the vibrating strips 16 are secured.

It will be observed that every part of the body 7 is free to vibrate. This is a great advantage over the cones heretofore used as diaphragms in loud speakers wherein the body terminated in an apex forming an integral part of the diaphragm and which apex is always rigid and, therefore, constitutes a "dead spot" incapable of vibration. The elimination of the apex likewise eliminates rigidity, and this in turn results in the elimination of muffling, thereby avoiding distortion.

It, therefore, appears that applicant's body portion 7 which defines a frusto-conical tube (the smaller opening 11 thereof constituting the throat and the larger opening the mouth), is a diaphragm which will respond to and amplify the vibrations set up in the vibrating strips 16 by the driving rod of the sound reproducing apparatus.

The sound reproducing apparatus may be of any preferred form, it being understood that the driving rod of the sound reproduc-

ing apparatus is secured in any suitable manner to the connecting sleeve 20.

What is claimed is:

1. An acoustical device comprising a diaphragm, said diaphragm defining a frusto-conical tube, the smaller opening in the tube defining the throat of the acoustical device, a connecting sleeve secured to the sound reproducing apparatus, and a series of spaced rods defining vibrating members secured to the sleeve and to the periphery of the throat. 70

2. An acoustic device, comprising a conical truncated diaphragm, a connecting sleeve secured to the diaphragm, and spaced rods defining vibrating members secured to the sleeve and to the periphery of the diaphragm, said rods being positioned in diverging relation to form a connecting spider. 80

3. An acoustic device, comprising a conical, truncated diaphragm, a connecting sleeve secured to the diaphragm, spaced rods defining vibrating members secured to the sleeve and to the periphery of the diaphragm, said rods being positioned in diverging relation to form a connecting spider, and means joining the converging ends of said rods. 85

4. An acoustic device, comprising a conical, truncated diaphragm, a connecting sleeve secured to the diaphragm, spaced rods defining vibrating members secured to the sleeve and to the periphery of the diaphragm, said rods being positioned in diverging relation to form a connecting spider, and means joining the converging ends of said rods, said means acting as connecting means for an actuating unit. 95

5. An acoustic device, comprising a frusto-conical diaphragm, and an actuating means joining the smaller end of said diaphragm with an actuating unit, said means forming a spider. 105

6. An acoustic device, comprising a frusto-conical diaphragm, and an actuating means joining the smaller end of said diaphragm with an actuating unit, said means forming a spider including diverging fingers. 110

7. An acoustic device, comprising a frusto-conical diaphragm, and an actuating means joining the smaller end of said diaphragm with an actuating unit, said means forming a spider including diverging fingers, said fingers being arranged in conical formation. 115

Signed at New York, in the county of New York and State of New York, this 13th day of December, 1927.

MAX PAUL BONNAT.
